United States Patent

Des. 238,661
Patented Feb. 3, 1976

238,661

ORAL THERMOMETER

Zsigmond L. Sagi, Parsippany, and Berel Weinstein, Fort Lee, N.J., and John Pardo, Yonkers, N.Y., assignors to Bio-Medical Sciences, Inc., Fairfield, N.J.

Filed Jan. 28, 1974, Ser. No. 437,000

Term of patent 14 years

Int. Cl. D10—04

U.S. Cl. D10—57

FIG. 1 is a top plan view of an oral thermometer showing our new design;

FIG. 2 is a front elevational view thereof;

FIG. 3 is a bottom plan view thereof;

FIG. 4 is a left end elevational view thereof;

FIG. 5 is a right end elevational view thereof.

We claim:

The ornamental design for an oral thermometer, as shown and described.
